UNITED STATES PATENT OFFICE.

FREDERICK JAMES PARKS, OF NEW YORK, N. Y.

DESIGN FOR AN ENVELOP.

47,569.

Specification for Design.

Patented July 13, 1915.

Application filed March 25, 1914. Serial No. 827,237. Term of patent 3½ years.

To all whom it may concern:

Be it known that I, FREDERICK JAMES PARKS, a citizen of the United States, and a resident of the city and State of New York, have invented a new, original, and ornamental Design for Envelops, of which the following is a specification, reference being had to the accompanying drawing, forming part thereof.

The figure is a face view of an envelop, showing my new design.

I claim:

The ornamental design for an envelop, as shown.

In witness whereof I have hereunto signed my name in the presence of two subscribing witnesses.

FREDERICK JAMES PARKS.
